STRIPPING MACHINE

Edward L. Taylor, Baltimore, Md.

Application February 1, 1949, Serial No. 73,980

2 Claims. (Cl. 93—36)

1

The present invention relates to a machine for stripping waste material from scored blanks cut from sheets of fibrous materials such as paper, cardboard, cellophane and like materials.

Under the present manufacturing methods, the complete blanks are usually scored, together with any additional openings or cut-away portions, from a standard sheet. For example, in a large number of cases these blanks are so designed as to form containers when folded, and frequently carry windows or other cut-out portions. Their openings are cut or scored in the same manner as the blank itself and in most instances are more difficult to remove from the blank than the blank itself from the sheet. In the past, for the most part, they have been removed by hand, using a small mallet. This is a slow and expensive process and while attempts have been made to solve this problem, there appears to be no machine at present which will perform this task in an efficient and satisfactory manner, and it is with this need in mind that the present apparatus has been developed.

One of the principal objects of the invention is to provide a simple and practical machine which may be readily adapted to a number of stripping operations.

Another object of the invention is to provide a machine of this type which is so constructed that a large number of blanks may be stripped in one operation.

A further object of this invention is to provide a stripping machine in which the stripping elements may be readily removed and replaced.

Still another object of this invention is to provide simple and effective stripping elements.

A still further object of this invention is to provide a combination die and guiding element for the blanks for facilitating changes from one form of blank to another.

While several objects and advantages of the invention have been pointed out, other objects and advantages will become apparent as the nature of the apparatus is more fully disclosed consisting in the novel construction, combination and arrangement of parts shown in the accompanying drawing and detail description forming a part of this specification and in which:

Figure 1 is a side elevation showing the improved stripping machine.

Figure 2 is an enlarged fragmentary sectional view taken along line 2—2 of Figure 1.

Figure 3 is an enlarged top plan view of a blank guide and die member.

Figure 4 is an enlarged fragmentary sectional view taken along line 3—3 of Figure 3.

Figure 5 is the front end view of the blank guide and die member.

Figure 6 is a top plan view of a modified form of the blank guide and die member.

2

Figure 7 is a front end view of the modified form of guide shown in Figure 6.

In the embodiment of the invention the machine includes generally a frame, a bed, a fluid operated piston and means for carrying out the stripping operation.

The machine is particularly adapted for stripping waste material from formed blanks which have been scored in a previous operation. The 10 machine includes a frame 10 and a horizontal bed 12. At one side of the frame there is a piston supporting bracket 14. This bracket may be part of the frame 10, or it may be separate and welded or bolted to the frame as shown by the 15 bolts 16. On the bottom of the frame there are provided casters 18 in order that the machine may be portable and moved to various locations where it is most advantageous to carry on the operation.

20 Supported upon the frame is a fluid compressor 20 which is preferably operated by an electric motor and a storage tank 22. The fluid is fed from the tank to a valve 24 by the pipe 25 and is directed into one or the other of the pipes 26 and 28 by operating the foot pedal 30.

25 Secured to the bracket 14 by the bolts 31 and 32 is a cylinder 34 which is mounted perpendicular to the bed 12. Within the cylinder is a fluid operated piston to which is connected a piston connecting rod 36. Connected to the upper end of the cylinder 34 is the fluid feed pipe 28 and connected to the opposite end of the cylinder is the fluid feed pipe 26. Connected to piston rod 36 is a coupling 38 which is adapted to receive 30 the shank 40 of a stripping tool 42. Surrounding the coupling 38 is a rotatable collar 44 held in place by a fixed collar 46. The collar 44 is secured to the piston rod 36 by the set-screw 48. Fixed to the collar 44 is a rod 50 which is adapted 35 to operate within a slotted guide member 52 for guiding the stripping tool along a predetermined path during its operation. The slotted guide member 52 is secured to the bracket 14 by the bolts 53 and 54.

40 The cylinder 34 is adjustable vertically of the support 14 by moving the securing bolts 31 and 32 along the slots in the bracket as indicated at 14' in Figure 2.

45 The die is formed in a die plate, which also 50 may act as the bottom surface of the blank guiding member, however the blank guide and die plate may be formed separately if desirable. In the present illustration the die plate is shown as forming a part of the blank guide member and in most cases this is the most practical way of 55 constructing the guide and die.

In Figures 1, 3 and 5 is illustrated a stripper for cutting out portions of a folding box. The die 62 is first formed in a die plate 63 about which 60 is built side walls 64 and 65 and a top member

66 or other means to limit the number of blanks to be carried in the blank guide member for any one stripping operation. In some instances it may be found that by leaving the top open and using a narrow strip along the inner top face of the walls 64 and 65 that the handling of the blanks may be accelerated, particularly if the blanks are small.

Referring particularly to Figures 3 and 5 the blanks 6 are stacked one upon the other as shown, the height of the walls 64 and 65 being such that a predetermined number of blanks may normally be placed into the machine for any one operation, and which also prevents the machine from being overloaded. In this particular blank, portions 60' and 60'' are to be removed which have already been scored during the cutting of the blank.

The die member itself 62 is slightly larger than the scored lines 67 and 67' on the blank, or in any case the edge of the die member is slightly over the scored line of the blank in order that the waste material will not normally contact the side of the die and allow a certain amount of flexibility between the edges of the blanks from which the waste is being stripped. It has been found if the die is substantially the same size as the waste portion, or is located too close to the score line the machine will jam and/or the edges of the blank will be raggy.

The stripper 42, 42' is constructed somewhat along the same principle as the die in that it is slightly narrower than the scored portions 60' and 60'' or on the opposite side of the score line from the die. This allows for a certain amount of flexibility on the waste side of the scored line, which prevents binding of the scrap particles along the edge of the blank as they are forced down one upon the other, out through the dies 62 and 62'. The stripper is fastened to the piston through the piston rod and is operable perpendicularly to the die plate 63, by fluid pressure, preferably air, or other gaseous substance, although the invention is not limited to gases to operate the piston as in some instances, it may be just as practical to use one of the well-known hydrous liquids.

The pressure used in operating the piston is also of great importance in the satisfactory operation of the machine. The pressure should be such that under normal conditions it would strip the waste material from the several blanks, but in case of a jam the pressure should not be such as to tear, or injure the blanks. By reversing the action of the stripping tool several times, the waste will usually be easily expelled. By this arrangement a large number of blanks may be processed at once with a minimum amount of damage, whereby under previous methods there was always considerable waste in damaged blanks.

Figures 6 and 7 show a modified form of die and blank guide member 68. In this arrangement several operations may be carried out on a single stock of blank, for example, the blank guide is formed with a detachable base 70, which is positioned and clamped to the bed 12 of the machine by the bolts 71, the base is provided with a back guide 70' and a plurality of holes 70'' for positioning the blank guide member. In this instance, the blanks 74 to be stripped consists of a series of openings 75, 76 and 77. As the spread of the strippers may be too great in some cases to perform satisfactorily, this arrangement provides for stripping of the blank by moving or shifting the die and guide member along the base 75

75 As illustrated, the stripping element 78 is positioned to remove the waste in the openings 75 in its first operation, after which the guide may be moved along its base 70 when the openings 76 may be removed and the same for openings 77. In order to align the die with the stripping tool the guide 68 is provided with several pins 79 and 80, which are adapted to fit within the holes 70'' in the base 70 to position the guide and die in the several operating positions. This modification is illustrative only of one way in which a large pile of blanks may be stripped where it would not be practical to strip the complete blank in one operation.

15 In the operation of the machine, the guide for the blanks must be constructed for that particular size blank. The base of the guide is provided with the proper shaped die as previously described. The guide and die may be constructed of any suitable material such as wood, fiber, metal, plastic or the like. Also a stripping tool such as that shown in Figure 1 is also constructed in conformity with the scored blank to contact the waste material to be stripped from the blank 20 as also previously described. The movement of the stripper of course must move entirely through the stock of blanks during each operation to clear all the waste from all the blanks. The blank guide is then fastened to the bed 12 by the bolts 25 15 in alignment with the stripper 42. If it is necessary to rotate the stripper, either one way or the other, the set-screw 48 may be loosened and rotated within the collar 44 until properly located when it is again tightened. The fluid pressure is determined for that particular operation, less pressure being required for a small stripping job than there is for one of greater size or area. After the blank guide, die and stripper have been properly aligned and set up as shown 30 in Figure 1, the blanks 69 are inserted within the guide. By depressing the foot pedal 30 to the position as shown by the dotted line 30', fluid will be directed through the pipe 28 to the top of the cylinder 34, forcing the stripper through the 35 guide and the blanks expelling the waste through the die and the base of the machine. When the foot pedal is released the fluid pressure is reversed and the pressure enters the bottom of the cylinder forcing the piston and stripper up and out of the die and blank guide. Normally the 40 valve 24 operates to keep the pressure in the bottom of the cylinder and the stripper withdraws and only when the pedal 30 is depressed is the pressure transferred to the opposite end of the 45 cylinder. 50

55 While one form of the invention has been illustrated and described in detail, it is not intended that it be limited to this particular arrangement as various changes in the details of construction 50 may be resorted to without departing from the spirit of the invention, and only so far as the invention has been particularly pointed out in the accompanying claims is the same to be limited.

60 I claim:

65 1. A stripping machine for stripping waste material from stacks of scored cardboard blanks, comprising a frame, a bed supported by said frame, a member operable perpendicular to the upper surface of the bed, a die of substantially the same configuration as the score lines of the blanks supported on the upper surface of the bed, the edge of the die formed to extend slightly outwardly from and along the said scored 70 lines of the blanks, a stripping tool of substan-

tially the same configuration as the scored lines of the blanks carried by the member and adapted to pass slightly inwardly from and along the opposite side of the scored lines, a stack guide having three vertical walls arranged in U-formation on the bed for positioning the scored lines of the stack along lines substantially equidistant from the edges of the die and the stripping tool and means for controlling the operation of the member.

2. In a stripping machine as defined in claim 1, a strip at the upper end of the guide for limiting the number of blanks to be inserted in the guide at any one time.
